[57] CLAIM

The ornamental design for a weaving machine, as shown.

DESCRIPTION

FIG. 1 is a perspective view of a weaving machine, showing my new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof; and,

FIG. 7 is a bottom plan view thereof.

The design is shown broken away to indicate indeterminate length.
